US0D1103124S

(12) **United States Design Patent** (10) **Patent No.:** **US D1,103,124 S**
(45) **Date of Patent:** **** Nov. 25, 2025**

(54) **WALL WIRELESS REMOTE**

(71) Applicant: **Foshan Jianfeng Electronic Technology Co., Ltd.**, Foshan (CN)

(72) Inventor: **Wenni Xu**, Foshan (CN)

(**) Term: **15 Years**

(21) Appl. No.: **29/844,505**

(22) Filed: **Jun. 29, 2022**

(51) **LOC (15) Cl.** **14-03**

(52) **U.S. Cl.**

USPC **D13/168**

(58) **Field of Classification Search**

USPC D13/123, 133, 152, 154, 156, 158, 160, D13/162, 162.1, 163, 164, 168, 169, 170, D13/171, 173, 174, 177, 178, 184, 199; D14/128, 188, 218, 358, 385, 456, 496; D8/350, 351, 352, 353

(57) **CLAIM**

The ornamental design for a wall wireless remote, as shown and described.

DESCRIPTION

FIG. 1 is a perspective view of a first embodiment of the wall wireless remote showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

The broken line portion of the drawings is included to show portions of the wall wireless remote that form no part of the claimed design.

1 Claim, 7 Drawing Sheets
